UNITED STATES PATENT OFFICE.

THOMAS V. PLICE, OF ASHLAND, OHIO, ASSIGNOR TO W. V. B. TOPPING, OF ASHLAND, OHIO.

BARN-DOOR HANGER PART.

1,105,918.

Specification of Letters Patent. Patented Aug. 4, 1914.

Application filed May 23, 1912. Serial No. 699,113.

To all whom it may concern:

Be it known that I, THOMAS V. PLICE, a citizen of the United States, resident of Ashland, county of Ashland, and State of Ohio, have invented a new and useful Improvement in Barn-Door Hanger Parts, of which the following is a specification, the principle of the invention being herein explained and the best mode in which I have 5 contemplated applying that principle, so as to distinguish it from other inventions.

My invention relates to door hanger parts and particularly to that part of barn door hangers which is adapted to be secured to 10 the upper end of the door.

The object of the invention is to produce a barn-door hanger part simple in its construction and efficient in its operation.

The said invention consists of means here- 20 inafter fully described and particularly set forth in the claim.

The annexed drawing and the following description set forth in detail certain means embodying my invention, the disclosed 25 means, however, constituting but one of various mechanical forms in which the principle of the invention may be applied.

In said annexed drawing: Figure 1 represents a side elevation of a door hanger part 30 embodying my invention, showing a fragmentary portion of a door in vertical trans- 35 verse section. Fig. 2 represents a front elevation of such hanger part. Fig. 3 represents a rear elevation of the upper portion 40 of said part and fragmentary door portion. Fig. 4 represents, in perspective, a detail of 45 the said hanger part.

In the illustrated embodiment of my in- 40 vention, A represents a door to which the hanger part is to be secured. Said hanger part comprises in its structure a main or 45 body portion B, which consists of a plate adapted to be secured to one face of the door as shown, by means of suitable screws 50 or other fastening devices. In the lower central part of the plate is a guide a, formed by cutting and bending outwardly a portion of the plate. This guide is provided with a central circular aperture a' (shown in 55 dotted lines in Figs. 1 and 2.) The upper portion of the plate is cut and bent to form two outwardly projecting guide lugs a² a² and an inwardly projecting lug a³ adapted to be secured to the upper edge of the door.

Lugs a² a² form between them a guiding 55 space in which is movably mounted a vertically adjustable member C, whose lower end is threaded and projects through the aperture a' in lug a. This lower end is provided with an engaging nut C' which bears 60 against the lower face of lug a. The upper end of member C is provided with a backwardly and transversely extending portion c in which is formed an undercut groove or slideway c'. Movably mounted in said slide- 65 way is a member D formed with an upward inner extension d adapted to be secured to the trolley (not shown) and a downward outer extension d'. The latter is provided with a threaded bore d² engaged by an ad- 70 justing screw d³ whose inner end is rotatably secured to the member C by means of a washer d⁴ held in place by riveting the inner end of said screw, as shown in Fig. 1.

By means of the above-described construc- 75 tion it will be seen that the door may, when heavy, be adjusted vertically by turning the nut C', and horizontally by turning the screw d³, the lugs a and a² forming a guide- 80 way for the movement of member C, as will be readily understood.

In order to retain the upper end of member C in position the outer part of the guiding space formed by lugs a² a² may be contracted, by suitably cutting such lugs, 85 whereby retaining projections a⁴ a⁴ are formed, as shown in the drawing.

As shown in the drawings, I prefer to make the slideway c' so that it will incline slightly in a downward and inward direc- 90 tion. By means of this arrangement the horizontal adjustment is accompanied by a slight vertical adjustment, which I find in some cases to be a desirable feature of my invention.

Having fully described my invention, 95 what I claim and desire to secure by Letters Patent is:—

In a door hanger part, the combination of 100 a main or body member adapted to be se- cured to the face of the door and provided with two upper outwardly projecting lugs forming a guide and a lower outwardly pro- jecting lug, likewise forming a guide; a member movably seated in said guides hav- 105 ing a lower threaded portion and an upper transversely projecting portion formed with a transverse slide-way; a nut on the said

threaded portion and below said lower guide; a member seated in said slide-way and movable therein, said member being provided with a downwardly projecting lug 5 on its outer end, and a screw having threaded engagement with said downwardly projecting lug and rotative engagement with

said slideable member, whereby the latter may be adjusted in its slide-way.

Signed by me this 8th day of April 1912. 10
THOMAS V. PLICE.
